UNITED STATES PATENT OFFICE.

SAMUEL C. BOND, OF WILMINGTON, DELAWARE, ASSIGNOR, BY MESNE ASSIGNMENTS, TO BOND BOTTLE SEALING COMPANY, A CORPORATION OF DELAWARE.

MACHINE FOR CAPPING BOTTLES.

No. 883,127.

Specification of Letters Patent. Patented March 24, 1908.

Application filed August 20, 1906. Serial No. 331,306.

To all whom it may concern:

Be it known that I, SAMUEL C. BOND, residing at Wilmington, in the county of New-
castle and State of Delaware, a citizen of the
United States, have invented or discovered
certain new and useful Improvements in
Machines for Capping Bottles, of which im-
provements the following is a specification.

The invention relates to that class of
bottle-capping mechanism which is em-
ployed for first compressing upon and in seal-
ing contact with a bottle-mouth a sealing
medium contained within a metallic cap
provided with a dependent flange or fingers,
and then constricting the flange of the cap
into locking engagement with a bead or
shoulder on the exterior of the bottle-mouth;
and it consists in certain improvements in
such mechanism by means of which the
operation can be efficiently and economically
performed.

In the accompanying drawings there is
illustrated a securing head embodying my
invention in its preferred form.

Figures 1 and 2 are sectional elevations of
the head, the parts in position at the begin-
ning and the end of the operation of securing
a cap on a bottle. Fig. 3 is a horizontal sec-
tion on the line III—III of Fig. 1. Figs. 4
and 5 are views similar to Fig. 1 illustrating
modifications of my improvement, Fig. 6 is a
horizontal section on a plane indicated by
the line VII—VII Fig. 4; Fig. 7 is a plan
view of the securing ring shown in Figs. 1, 2,
4, 5 and 6.

The bottle may be held or supported in
proper position relative to the head by any
suitable means, and the head is believed to
be adapted for use with any suitable mech-
anism for bringing it into operative relation
to the bottle, or the bottle into similar rela-
tion to the head. A great variety of mech-
anism suitable for that purpose is well
known to those skilled in the art, and need
not be illustrated.

Referring to the drawings, the casing 1 of
the head is preferably cylindrical in form as
shown, and is provided with a bottom wall 2
converging upwardly to form a bottom
opening in the head of slightly greater diam-
eter than the mouths of the bottles to be
opened. Such conical form of the bottom
of the head is not essential, but it is preferred
for the reason that it assists in the proper

axial alinement of the bottle for the capping 55
operation.

Within the casing is secured the sealing-
block 3, preferably as shown, by screwing an
upper flange or collar of said block within the
upper portion of the inner wall of the casing. 60
Below this flange or collar the block is
formed of a diameter preferably a very little
greater than that of the bottom opening in
the casing, and in the annular space thus
left between the block and the casing below 65
their junction, is arranged the annular plun-
ger 4. This plunger is connected preferably
by means of bolts 5, as shown, and which
pass freely through openings through the
overhanging flange or collar of block 3, to an 70
upper cross-head or plate 6, fastened to or
integral with the stem 7. A resilient cush-
ion as spring 8 is interposed between the
head and the plate 6, said spring being
adapted to hold the ring plunger in raised 75
position as shown in Fig. 1 and having suf-
ficient tension to exert the desired pressure
on the cap during the sealing operation. It
is preferred to arrange the spring in axial
openings in the block 3 and stem 7, as 80
shown. The block 3 is of a length such that
its lower face is slightly above a shelf 9
formed around the inner edge of the bottom
opening of the casing, and upon this shelf is
supported an annular constricting tool 10. 85
This tool is also preferably employed to sup-
port the cap, the flange of the cap, as shown
in Fig. 1, being gripped by the tool. For
that purpose the cap securing tool is resilient,
in order to permit the cap to be placed in 90
position, (either by hand or by any suitable
mechanical means), and then to hold the cap
with sufficient firmness. In order to receive
the top of the cap when so supported, as well
as for another purpose to be presently de- 95
scribed, the bottom face of the block 3 is
concave, as shown.

In the operation of capping the tool or part
directly operative on the flange of the cap to
cause it to engage the bead or rib on the bot-
tle, is caused to move inwardly by a move-
ment of the annular plunger independent of
the head, and during such movement of the
plunger the tension of the spring 8 is in-
creased, thereby causing the block 3 to exert 100
the desired pressure on the cap to compress
the packing in the latter and seat it tightly
on the end of the bottle neck. 105

The form of securing-tool which it is preferred to employ is illustrated in Figs. 1, 2, 4, 5, 6 and 7, and consists of an annular coil of fine steel wire, which is stiff enough to exert the necessary constricting pressure upon the flange of the cap, but still has sufficient internal resilience to accommodate itself to the usual irregularities in the cross-sectional contours of the mouths of the bottles to be capped. The latter result has heretofore been attained, it is believed, only by the employment of resilient or resiliently supported means for operating the securing-tool; whereas by making the tool itself internally resilient to the required degree, while at the same time preserving the rigidity necessary to the desired action of the tool on the flange of the cap, much more evenness and certainty of sealing is believed to be attained. The spiral wire 10 preferably loosely incloses a solid ring 11, sufficiently smaller in cross-sectional diameter to permit the necessary play of the wire 10, but the employment of the inner ring is not considered essential. In operation, the stem 7 is attached to any suitable mechanism, varieties of which are well known to those skilled in the art, for imparting to the head a reciprocating movement with relation to the mouth of a bottle supported in axial alignment therewith. Or, as is equally well known, the bottle support and the bottle may be moved, and the head be held stationary by means of the stem 7. The spring 8 is of strength sufficient to withstand a pressure equal to that which is desired to be exerted in compressing the sealing-disk in the cap upon the bottle-mouth, and normally holds the ring 4 firmly in its upper position, as shown in Fig. 1, with its upper face bearing against the lower face of the overhanging collar or flange of block 3. When the bottle-mouth to be sealed has entered the bottom opening of the casing and the cap pressed against the lower face of the block 3, the pressure exerted upon the stem 7 and thence through the spring, 8, causes the compression of the sealing-disk within the cap upon the bottle-mouth. When the pressure necessary to the proper compression of the sealing-disk has been attained, the spring 8 will yield, and the continued application of pressure to the stem 7 will, through plate 6 and bolts 5, cause the ring 4 to move downwardly within the casing and through means hereafter described, cause a constriction of the tool 10 in contact with the flange around the latter. In the construction shown in Figs. 1, 2 and 3 the constriction or inward movement of the tool is effected by a series of radially arranged fingers 12 having their inner ends shaped to the contour of the tool 10, while their outer ends are in engagement with the plunger 4. The outer ends of the fingers are rounded and project into a groove 13 in the lower end of the plunger 4. It is

preferred that the outer ends of the fingers should have a yielding abutment in the groove as the split ring 14. The tool 10 is supported as stated by a shelf or ledge 9 in proper relation to the position of the bottle neck during the sealing operation and as the plunger 4 moves in the head the outer ends of the fingers, which normally form an acute angle with the axis of the head, are moved down thereby forcing the tool inward along the shelf, and causing it to act constrictively on the flange of the cap. This constrictive movement of the tool can be effected in other ways, as for example in Figs. 4 and 6, the tool is acted on in opposite directions by straps 15, which have their ends connected respectively to the lower ends of toggle fingers 16 supported by the shelf or ledge 9^a of the head. These fingers are oppositely inclined and their upper ends bear against an abutment or shoulder 17 on the plunger 4^a. These fingers have normally such an inclination that when the plunger is moved down, the lower ends of the fingers will slide outward along the shelf 9^a drawing the loops formed by the straps 15 towards each other thereby constricting the tool. It will be observed that the straps so embrace or surround the tool that each acts constrictively through an arc of more than one hundred and eighty degrees, the constrictive action of one loop or strap overlapping that of the other loop or strap.

It will be observed that the direction of action of the plunger on the tool is at an angle less than a right angle to the axis of the tool, the plunger acting as a wedge. This wedge-like action is produced in the constructions shown in Figs. 1, 2, 4 and 6 by the interposition of inclined fingers between the tool and the plunger. As shown in Fig. 5 the plunger may be constructed with an inclined beveled portion 18 which will act directly on the tool causing a constriction of the latter.

I claim herein as my invention:

1. In a bottle capping machine the combination of a head having a cap bearing portion or block, an annular tool having independently movable portions, a plunger movable relatively to the head for effecting a constricting movement of the tool, and a yielding cushion or spring interposed between the plunger and tool.
2. In a bottle capping machine an annular cap securing tool, consisting of portions the inner walls of which are capable of independent radial movement when acting on the cap.
3. In a bottle capping machine an annular cap securing tool formed of wire bent to form a spiral.
4. In a bottle capping machine the combination of a head, an annular cap securing tool having its inner wall formed of portions radially movable independently of each

other, and adapted to support the cap in position to receive the end of the bottle neck.

5. In a bottle capping machine the combination of a head, an annular cap securing tool consisting of portions the inner walls of which are capable of independent radial movement when acting on the cap, and means including a resilient member for forcing said portions into operative engagement with the cap.

6. In a bottle capping machine the combination of a head, an annular cap securing

tool consisting of portions, the inner walls of which are capable of independent radial movement when acting on the cap and adapted to support the cap in position to receive the end of the bottle neck. 15

In testimony whereof, I have hereunto set my hand.

SAMUEL C. BOND.
